UNITED STATES PATENT OFFICE.

CHARLES SPITZ, OF NEW YORK, N. Y.

BUNSEN BURNER.

Application filed May 3, 1921. Serial No. 466,515.

To all whom it may concern:

Be it known that I, CHARLES SPITZ, a citizen of the United States, and a resident of 92 William Street, New York city, in the 5 county of New York and State of New York, have invented certain new and useful Improvements in Bunsen Burners, of which the following is a specification.

My invention relates to gas burners and 10 has for its object the automatic proportioning of the air to the gas and the thorough commingling of the two gases to form an intimate mixture adapted to burn completely and with the development of the maximum combustion temperature.

The gas burners used generally on gas stoves are of the true Bunsen type in which the gas stream entering a bell shaped chamber draws in air, by induction, to mix with 20 the gas stream in passing through the chamber or passage to the burner proper. The mouth of this bell chamber is usually fitted with an adjustable shutter for limiting the amount of air that may enter. The object 25 of this shutter is to prevent a mixture of air and gas so explosive as to flash back into the mixing passage and burn at the gas nozzle. This flashing back occurs most persistently with the burners having short 30 mixing chambers and in these short burners it is necessary to so set the shutter at the mouth of the bell chamber, that a mixture relatively rich in gas is obtained to prevent 35 flashing back. This gives an inefficient and smoky flame of poor heating quality. The flashing back is such a nuisance that the gas service companies send men 40 around to inspect and adjust the gas stoves to minimize it, so that generally speaking everyone using a gas range is burning gas inefficiently for the purpose of avoiding a disagreeable condition that cannot be entirely overcome.

It is the object of my invention to provide 45 a mechanism that without requiring a single adjustment will make and utilize the correct mixture of air to gas for perfect combustion; that will effectually prevent flashing back even in the shortest type 50 of mixing chambers; that will operate through a wide range of flame adjustment; that will give a greater flame temperature or save a proportional amount of gas when operating at the same temperature; that will 55 eliminate odors from the flame and avoid the sooting up of cooking utensils.

The several objects set forth above and others that will later on appear are now to be described and are illustrated in the accompanying drawings forming part of this 60 specification.

Similar characters of reference denote like or corresponding parts throughout the several views of which Fig. 1 is a vertical longitudinal section of my gas burner, Fig. 65 2 is a cross section on the line A—A of Fig. 1; Fig. 3 is a vertical longitudinal section of a modification of Fig. 1 and Fig. 4 is a cross section on the line B—B of Fig. 3.

Referring particularly to Fig. 1 of the 70 drawings numeral 1 represents a gas pipe usually positioned across the front of the gas stove and into which the gas cocks supplying the several burners are tapped at regular intervals, such a cock is shown at 2, 75 the handle of which 3 serves to regulate the flow of gas to the burner through the drilled passage 4. A nozzle 5 is shouldered down as shown and is adapted to receive the socket 6 fitted into the end of the cone shaped mixing chamber 7. Just beyond the end of the gas nozzle 5 is a small propeller fan 8 mounted to turn freely on the axle 9 which in turn is supported by the strips 10 and 11, secured to the wall of the mixing chamber 85 by the rivet 12, or in any other well known manner. The small end 13 of the mixing chamber may be fitted into the socket 14 of the cast burner (not shown) and held by the set screw 15 in the usual way. The entire 90 structure, mixing chamber and burner, are adapted to be fitted in place by slipping the socket 6 over the shouldered nozzle end 5.

My invention operates as follows; the cock 2 being opened, a stream of gas issues from 95 the nozzle 5 and impinges directly on the vanes of the fan wheel 8 causing this wheel to spin rapidly. The moving vanes are at such an angle as to cause air to be drawn into the mouth of the mixing chamber (see 100 arrow a, b, and c) and in passing the wheel to be thoroughly mixed with the gas stream so that immediately after passing the wheel a perfect mixture of the air and gas has been formed. This mixture as it goes forward 105 forces the air occupying the mixing chamber and burner out ahead of the gas and air mixture very much in the same fashion that a plunger would with the result that when the mixture issues from the 110 burner apertures it is of the same quality as formed by the fan, so does not flash back.

The size of the fan determines approximately the relative volumes of gas and air and this holds for changes in the volume of gas admitted by the nozzle.

5 In Figs. 3 and 4 the mixing chamber 16, is shaped somewhat like the casing of a centrifugal blower. The freely turning wheel 17 is mounted on a spindle 18 supported by the straps 19 and 20. Openings 21 and 22 10 on opposite sides of the casing serve to admit air when the fan wheel is rotated and to deliver the air in the directions of the arrows *e*, *f*, *g*, *h* and *k*. The casing is provided at the back with a socket 23 fitting 15 over the shouldered nozzle 5. The forward end of the mixing chamber casing is fitted into the burner socket 14 and held by a set screw 15. The operation of this modified burner is the same as Fig. 1 with the gas 20 passing the nozzle and impinging on the wheel vanes and causing the wheel to rotate, the air entering the wheel at each side through the openings 21 and 22 and being 25 mixed by the wheel with the gas, the resultant mixture passing forward into the burner.

Having thus fully described my invention

so that anyone skilled in the art may make and construct the same and without strictly confining myself to the exact construction 30 and arrangement of parts as shown, I claim:

1. In an air to hydrocarbon gas proportioning device for Bunsen burners, a gas conduit, a cylindrical mixing chamber tangentially disposed in relation to the gas 35 conduit, a fan wheel freely rotatable in the mixing chamber, air openings centrally located in the end walls of the mixing chamber and a gas nozzle adapted to direct a stream against the fan wheel for rotating the same. 40

2. In an air to hydrocarbon gas proportioning device for Bunsen burners, a gas conduit, a cylindrical mixing chamber tangentially disposed in relation to the gas conduit, a fan wheel freely rotatable in the mixing chamber, air openings centrally located 45 in the end walls of the mixing chamber and a gas nozzle adapted to direct a stream against the fan wheel and into the gas conduit. 50

Signed at New York City, in the county of New York and State of New York this 28th day of April A. D. 1921.

CHARLES SPITZ.
